EDWARD I. CHAPIN, OF SYRACUSE, NEW YORK, ASSIGNOR TO CHAPIN-SKELTON CORPORATION, OF SYRACUSE, NEW YORK, A CORPORATION OF NEW YORK.

CLOTHES-PRESSING MACHINE.

Application filed June 6, 1923. Serial No. 643,756.

This invention relates to a garment pressing machine in which a movable pressing element is moved to its pressing position by the straightening of a toggle connection between that element and the frame of the machine, and is moved from its pressing position by an overbalancing counter-weight which, incidentally flexes the toggle after its members have been slightly deflected from a straight line to permit the automatic opening movement of said element by the counter-weight.

In most of the machines now in common use, the toggle is moved to its straightened position by means of a pedal lever and is adjustably connected to the movable pressing element for varying the pressure upon the garment.

This adjustment should be made to impart relatively high pressure to the garment in order that the shaping of the latter may be more permanent, thereby requiring considerable pressure upon the pedal lever, which, of course, renders the work more laborious than would be the case if the adjustment were made for producing a lighter pressure and, inasmuch as this adjustment may be made at the will of the operator, it is frequently done to lighten the work, resulting in imperfect shaping of the garment, which of course, is unsatisfactory to the patron and detrimental to the reputation of the machine.

Furthermore, the garments are either brought to the machine for pressing in a more or less dampened condition or they are slightly dampened by the application of steam thereto during the pressing operation, so as to render the garment more pliable for shaping under pressure and under these circumstances, the moisture imparted to the garment must be removed or completely evaporated by the heat imparted thereto by the pressing elements in order to impart a more permanent shape to the garment and also to prevent wrinkling of the garment after it has been pressed and laid aside as would be the case if it contained any moisture.

The main object, therefore, of this invention is not only to assure the application of sufficient pressure to the garment to properly shape the same, but also to maintain that pressure under the heat of the

pressing elements for a sufficient period of time to assure the thorough drying of the garment before the removal from the machine without undue loss of time so that the net result may be greater efficiency and increased production.

In other words, I have sought to straighten the toggle and thereby to force the pressing head to its pressing position by means of a motor driven rotary cam and to provide means for automatically locking the toggle in its straightened position and thereby, to hold the pressing head in its pressing position for indefinite periods of time according to the nature of the work operated upon or until released by the voluntary act of the operator.

Another object is to provide simple and efficient means controlling the operation of the cam and thereby controlling the closing movement of the press head upon the work, particularly while the latter is being spread out by hand upon the buck preparatory to pressing and incidentally, reducing the liability of injury to the hands of the operator by contact with the heated head or by being caught between the pressing elements.

Other objects and uses relating to specific parts of the machine will be brought out in the following description.

In the drawings:

Figure 1 is a rear elevation of a garment pressing machine embodying the various features of my invention.

Figure 2 is a side elevation, partly in section, taken on line 2—2, Figure 1.

Figures 3 and 4 are enlarged detail sectional views taken respectively on line 3—3, and 4—4, Figure 1.

Figure 5 is a detail sectional view taken on line 5—5, Figure 1, portions of the frame being broken away.

Figures 6 and 7 are detail sectional views taken respectively in the planes of lines 6—6, and 7—7, Figure 5.

As illustrated, this machine comprises an upright frame —1— having front and rear brackets —2— and —3— rising from a horizontal ledge —4— upon which is mounted a work table —5—. A pair of pressing elements commonly known as a buck —6— and a press head —7— are mounted respectively upon the upper face of the bracket —2— and a rock arm or lever —8— which

latter is pivotally fulcrumed intermediate its ends at —9— upon the upper end of the bracket —3— to swing about a horizontal axis substantially parallel with the longitudinal centers of the buck —6— and head —7— and some distance to the rear thereof so as to leave a clear open space entirely around the marginal edges of the buck for convenience of manipulation of the garment thereon.

The upper portion of the rear bracket —3— is bifurcated as shown in Figure 1 to form opposite transversely spaced arms between and upon which the central portion of the rock arm or lever —8— is pivoted and supports at its front end, the press head —7—, while the rear end carries an adjusting screw —10— to which is pivotally connected at one end, a toggle —11— having its other end pivoted at —12— to the frame of the machine as shown in Figure 2.

The rear end of the supporting arm —8— for the head —7— is provided with a weighted member —13— adapted to overbalance the weight of the head —7— for opening the latter from the work when the toggle —11— is flexed from a straight line toward the position shown by dotted lines in Figure 2.

30 The pressing elements —6— and —7— may be provided with the usual steam chambers for heating and moistening purposes or may be heated by any other suitable heating means, the head being shown as provided with a steam inlet pipe —14— adapted to be connected to any available source of steam or hot water supply.

A handle —15— on the head —7— serves as a means for rocking said head upon its pivotal bearing —9— when desired against the action of the counter-weight —13—.

The toggle —11— preferably consists of a lower member —11'— and an upper member —11''— having their adjacent ends pivoted to each other at —16— to form a flexing joint, the axis of which is parallel with the pivotal bearing of the rock arm —8—, the upper member —11''— being pivotally connected at —17— to the adjusting screw —10— on the rear end of the arm —8—.

The lower member —11'— is pivoted intermediate its ends at —12— to the frame —1— and has its lower end provided with a weight —18— which serves to assist the movement of the toggle from its flexed position shown by dotted lines in Figure 2, to its straightened position shown by full lines in the same figure by its own momentum when started from its position of rest in a manner hereafter described to assure the straightening of the toggle and resultant closing of the press head upon the work.

The pivotal bearings —12— and —17— are also parallel with the pivotal bearing —9— of the press head, the bearing —12—

being some distance below the bearing —9— while the pivotal connection —17— is some distance to the rear of said bearing —9— so that when the toggle —11— is straightened, it inclines upwardly and rearwardly from the pivot —12—, while the joint —16— flexes rearwardly and downwardly and causes the lower member —11'— to assume approximately a horizontal position when the press head is fully opened, and the member —11''— assumes a substantially vertical position as shown by dotted lines in Figure 2.

Toggle straightening means.

An electric motor —20— is mounted upon the main supporting frame —1— some distance below the work table —5— with its armature shaft in a horizontal position and provided with a fly wheel —21— connected by a universal joint —22— to an extension —23— of said shaft, said extension being connected in turn to a worm shaft —24— which is journaled in a suitable gear case —25— and is provided with a worm —26— 90 at the rear of the machine.

A horizontal cam shaft —27— is also journaled in the gear case —25— at right angles to the shaft —24— and is provided at one end with a cam —28— keyed thereto 95 to rotate therewith in substantially the same plane as that of the toggle —11— for moving the latter to a straightened position in a manner presently described.

The opposite end of said shaft is provided with a clutch collar —29— having a clutch pin —30— movable axially therein into and out of engagement with a companion coaxial clutch member —31— which is journaled in the gear case or housing —25— and upon the adjacent portion of the cam shaft —27— for relative rotation thereon.

This clutch member —31— is provided with a hub —32— extending into the gear case —25— and to which is keyed or otherwise secured, a worm wheel —33— meshing with the worm —26— and adapted to be rotated thereby for rotating the clutch member —31—.

The end of this clutch member —31— adjacent the clutch member —29— is enlarged and is provided with a series of axially extending openings —34— arranged in uniformly spaced relation about the axis thereof for receiving the clutch pin —30— which, when released is spring-pressed into one or the other of the registering openings —34— by means of a coil spring —35—, Figure 4, said clutch pin being provided with a stud or pin —36— projecting outwardly through an elongated slot —37— in the adjacent portion of the clutch member —29— for shifting the clutch pin into and out of any one of the registering openings —34— and thereby locking and unlocking the coupling mem- 130

ber —29— and cam shaft —27— to and from the coupling member —31— and worm gear —33—.

6 A clutch operating lever —38— is pivoted intermediate its ends at —39— to the outer end of the gear case —25— to rock about an axis parallel with that of the cam shaft —27— and is provided at its rear end with a cam —40— for engaging the stud or pin —36— and withdrawing the clutch bolt —30— from the clutch member —31— against the action of the spring —35— when the lever is rocked in one direction.

10 The front end of the lever —38— is connected by an upwardly extending link —41— to one arm of a bell crank lever —42— which is pivoted at —43— to a bracket —44— on the under side of the work table —5—.

15 The other arm of the bell crank lever —42— is connected by a forwardly extending link —45— to one arm —46— of a hand lever —47— which is pivoted at —48— to a bracket —49— on the underside of the work table —5—, Figures 5 and 6, within easy 20 reaching distance of the hand of the operator and serves as a part of the operating means for the clutch shifting lever —38— to control the operation of the cam shaft —27— and thereby to control the closing movement 25 of the press head.

20 A crank shaft —50— is journaled in suitable brackets —49— and —51— on the underside of the table —5— parallel with the axis of the pivot —48— and is provided at one 25 end with a detent —52— movable into and out of engagement with a shoulder —53— on the upper side of the hub of the hand lever —47— to normally hold said lever against upward movement until the detent 30 is tripped, the other end of said rock shaft —50— being provided with a hand lever —47'— somewhat similar to the hand lever —47— for rocking said shaft to trip the detent —52— and thereby to release the lever 35 —47— and allow the latter to be raised for shifting the cam lever —38— and clutch pin —30— controlled thereby.

30 The periphery of the clutch member —29— is preferably circular to form a 35 brake drum while the inner end of the clutch shifting lever —38— and cam portion —40— is preferably concave to form a brake shoe for engaging the periphery of the clutch member —29— to retard the rotation of the cam shaft —27— when the clutch pin —30— is withdrawn from the clutch member —34—, said shifting lever —38— being retracted by a spring —38'— which also serves to normally hold the brake surface as —40'— of the lever against the periphery of the clutch member —29—.

35 The cam —40— projects laterally from one side of the shifting lever —38— lengthwise of the periphery of the clutch member —29— and has its outer edge beveled in op-

posite directions from the high point thereof, the lower bevel being relatively long to permit the stud —36— to gradually ride up the incline thereof at the end of each revolution of the coupling member —29— for 70 automatically disconnecting said member from its companion clutch member —31— when the stud —36— reaches the high point of the cam.

75 The upper beveled surface is relatively short or abrupt so that when the adjacent end of the lever is rocked downwardly by the upward movement of the hand lever —47—, it will release the stud —36— and allow the spring —35— to force the clutch 80 pin —30— into the aperture —34— registering therewith, thereby locking the two clutch members together and causing the rotation of the cam shaft —27— with the cam —28— thereon in the direction indicated by the arrow, Figure 2.

85 The means for transmitting motion from the cam —28— to the toggle —11— consists of a forwardly and rearwardly extending lever —54— having its front end pivoted at 90 —55— to the frame —1— some distance below and parallel with the pivot —12— of the toggle arm —11'— and its rear end extended rearwardly and upwardly from the pivot —55—, and provided with a roller 95 —56— adapted to engage a bearing —56'— on the rear face of the toggle arm —11'— between the pivots —12— and —16—, the intermediate portion of said lever being provided with a stop —57— adapted to engage 100 a rubber buffer —58— on the base of the frame and thereby to limit the rearward flexing movement of the toggle and incidentally limiting the opening movement of the press head by the weight —13—.

105 A pair of levers —59— and —59'— are pivoted at —60— to a bracket —61— on the lower rear portion of the frame —1—, the lever —69— being connected by a link —62— to the lever —54— between the pivot —55— and stop —57—.

110 The rear end of the other lever —59'— is provided with a roller bearing —63— adapted to be engaged by the cam —28— as the latter is rotated in a direction indicated by 115 the arrow, thereon, Figure 2.

115 The lever —59— is provided with a rearward extension —64— underlying the adjacent end of the lever —59'— which in turn is provided with an adjustable screw stop 120 —65— at the rear side of its pivot —60— for engagement with the extension —64— for adjusting parts —59— and —59'— about their common pivot —60— and thereby to assure a sufficient movement of the 125 lever —54— to straighten the toggle by the maximum throw of the cam —28— acting upon the arm —59'— although it is evident that the arms —59— and —59'— may be rigidly secured to each other or made in-

tegral without departing from the spirit of this part of the invention.

The upper end of the toggle arm $11'$ is provided with a yielding buffer 66 adapted to engage a fixed stop as 67 on the frame 1 to limit the movement of the toggle to a substantially straight line from its normal flexed position.

- As the toggle 11 has been forced to its straightened position by the cam 28 , through the medium of the levers $59'$, 59 and 54 and links 62 , it is automatically locked in that position against rebound, by means of a catch 68 , Figure 2, pivoted at 69 to a bracket 70 which in turn is provided with a rearward extension $70'$ carrying a pivoted member 71 , the latter being adapted to be operated against an extension 73 of the catch 68 by the upwardly extending arm of the lever 54 as the latter is urged against the rear face of the toggle member $11'$ in straightening the toggle.
- A coil spring 74 is interposed between the pivoted member 71 and extension 73 to allow limited variation of movement of the member 71 by the lever 54 , and to retract said member 71 .
- A similar coil spring 75 is interposed between the catch 68 and bracket 70 to allow the latter to yield sufficiently to cause its hook-shaped extremity 76 to engage a pin 77 on the toggle arm $11'$ and also to force said catch out of engagement with the pin 77 when the lever 54 is returned by its own weight away from the toggle after being released by the continued rotation of the cam 28 or when the low point of the cam is registering with the roller 63 .

The heel of the pivoted member 71 is provided with a stop shoulder 78 adapted to engage the underside of the extension $70'$ to limit the rearward swinging movement of said member by its retracting spring 74 .

That is, after the toggle 11 has been straightened to force the press head to its straightened position, it may remain in that position at the will of the operator, but when the cam 28 returns to its starting position with its low point in contact with the roller 63 , the catch operating member 71 will have been released by the lever 54 and retracted to its normal position by the spring 74 thereby releasing the catch 68 and allowing the latter to be moved out of engagement with the pin 77 by the retracting spring 75 .

Under these conditions, the toggle may be flexed rearwardly and downwardly at the will of the operator through the medium of a pedal lever 80 which is pivoted at 55 coaxial with the pivot of the lever

54 and extends upwardly therefrom, the upper end of said pedal lever being adapted to engage the rear side of a pin or roller 81 on the weighted end of the toggle lever $11'$ as shown by full lines in Figure 1, and by dotted lines in Figure 2.

As soon as the toggle joint 16 is flexed from its straightened position, by the operation of the pedal 80 , the press head will be raised by its counterweight 13 thereby further flexing the toggle until its lower member $11'$ rests upon the retracted operating lever 54 ready for a repetition of the pressing operation.

Operation.

Assuming that the press head has been forced from its normally open dotted position, Figure 2, to its full line pressing position by a previous revolution of the cam 28 , and that the latter is in its starting position at the end of said revolution, as shown by full lines in Figure 2 in which case, the lever 54 and its actuating parts will assume the position shown by full lines while the catch 68 and its operating member 71 will assume the position shown by dotted lines in said figure; then the voluntary operation of the pedal lever 80 against the pin 81 will flex the toggle joint 16 rearwardly to break the toggle lock, and thereby permit the weight 13 to raise the head 7 and further flex the toggle 11 until its member $11'$ rests upon the retracted upper end of the lever 54 ready to begin another pressing operation.

The motor 20 and worm gear 33 driven thereby may be continuously rotated independently of the cam shaft 27 and when it is desired to press a garment, the latter is spread out upon the buck 6 and when properly arranged for pressing, the hand lever $47'$ directly under the table will first be operated by one hand, as the left hand, to trip the detent 52 after which, the other lever 47 will be operated to shift the cam lever 38 from the position shown by full lines to that shown by dotted lines in Figure 5, to withdraw the high point of the cam 40 from the stop pin 36 and allow the clutch pin 30 to be forced by the spring 35 into one of the registering apertures 34 in the then rotating clutch member 31 , thereby causing the rotation of the cam shaft 27 and cam 28 one complete revolution or until the stud 36 returns and rides to the high point of the cam 40 for withdrawing the clutch pin at which time, the revolution of the shaft 27 and cam 28 will cease, leaving the cam 28 in the position shown by full line Figure 2.

Each revolution of the cam 28 will cause the operation of the lever 54 to

force the toggle —11— to its straightened position which in turn will force the press head into pressing engagement with the work upon the buck —6— and at the same time, the upwardly extending arm of the lever —54— will force the member —71— against the extension —73— of the catch —68— to cause the latter to interlock with the pin —77— and thereby to prevent rebound of the toggle from its straightened position, which may remain straightened at the will of the operator or until released by the operation of the pedal —80—, it being understood that as soon as the cam —28— returns to its starting position, as shown in Figure 2, the lever —54— and its actuating parts will also return by their own weight to their normal positions ready for a repetition of the operation previously described.

20 I claim:

1. In a garment-pressing machine having a frame and cooperative pressing elements, one of which is movable toward and from the other, a retracting means for the movable pressing element, a toggle connecting the movable pressing element to the frame, a weight on one of the toggle members for assisting the movement of the toggle toward its straightened position, a motor, motor-driven means including a clutch for actuating the toggle from its extreme retracted position to a straightened position, and means including a cam for disengaging the clutch members when the toggle is straightened.

2. In a garment-pressing machine having a frame and cooperative pressing elements, one of which is movable toward and from the other, in combination with a toggle connecting the movable element to the frame for opening and closing the movable element and locking it in its closed position when moved to a straightened position, a power driven rotary cam; means actuated by the

45 cam for moving the toggle from its extreme flexed position to its straightened locking position, and means operable at will for flexing the toggle from its straightened position independently of the cam operated means.

50 3. In a garment-pressing machine having a frame and cooperative pressing elements, one of which is movable toward and from the other, toggle connections between the frame and the movable pressing element, retracting means for opening the movable pressing element and for flexing the toggle away from a straightened position, a motor, means actuated by the motor for forcing the toggle to a straightened position, a shoulder on one of the toggle members, a catch pivoted to the frame, and means actuated by the toggle-straightening means for forcing said

55 catch into engagement with said shoulder when the toggle is straightened to prevent rebound of the toggle, and means operable at will for flexing the toggle from its straightened position.

4. In a garment pressing machine having a frame and cooperative pressing elements, 70 one of which is self-opening and movable toward and from the other, toggle connections between the frame and movable element, a motor driven rotary cam, means for automatically stopping the cam at the 75 end of each complete revolution, means actuated by the cam for moving the toggle from its extreme flexed position to a straightened locking position and a pedal lever operable at will for flexing the toggle 80 from its straightened position.

5. In a garment pressing machine having a frame and cooperative pressing elements, 85 one of which is self-opening and movable toward and from the other, toggle connections between the movable element and frame, a rotary cam-shaft, a cam secured to the shaft, a continuously rotating motor, means including a clutch for transmitting rotary motion from the motor to the cam shaft, means operable at will to cause the engagement of the clutch, means for automatically disengaging the clutch at the end of each complete revolution of the cam shaft 90 and cam thereon, means actuated by the cam during one complete revolution thereof for moving the toggle from its extreme flexed to its straightened locked position, and a pedal lever operable at will for flexing the toggle from its straightened position to permit the opening of the movable pressing element.

100 6. In a garment pressing machine having a frame and cooperative pressing elements, 105 one of which is movable toward and from the other, toggle connections between the movable pressing element and frame, means for retracting the movable element and for flexing the toggle from its straightened position, a lever pivoted to the frame for forcing the toggle to a straightened position, said lever being retractable independently of the toggle, a motor, and means including a rotary cam actuated by the motor for operating said lever to force the toggle to its straightened position, and to allow the retraction of the lever during one revolution of the cam.

110 7. A garment pressing machine, as in claim 6, in which the cam operating means 120 includes a clutch, and means for releasing the clutch at the end of one revolution of the cam.

In witness whereof I have hereunto set my hand this 24th day of May 1923.

EDWARD I. CHAPIN.
